UNITED STATES PATENT OFFICE.

ARTHUR J. WEBSTER, MICHEAL W. HALL, AND WILLIAM E. STADLER, OF BAKERSFIELD, CALIFORNIA.

PUMP FOR DEEP WELLS.

SPECIFICATION forming part of Letters Patent No. 711,804, dated October 21, 1902.

Application filed September 30, 1901. Serial No. 77,094. (No model.)

To all whom it may concern:

Be it known that we, ARTHUR J. WEBSTER, MICHEAL W. HALL, and WILLIAM E. STADLER, citizens of the United States, residing at 5 Bakersfield, in the county of Kern and State of California, have invented certain new and useful Improvements in Pumps for Deep Wells, of which the following is a specification.

Our invention relates to pumps, particularly for use in deep wells, such as oil-wells, where a sandy or heavy oil is to be raised. A commercially successful or practical pump for this purpose must be simple in construction, durable, comprised of parts easily assembled and readily replaceable, and be efficient in operation. The pump herein presented embodies a structure fulfilling these requirements, and, in addition, it includes other features adding to its general efficiency.

It is well known that the diameter of a deep well is comparatively small, and the valve mechanism and other operating parts of the pump herein presented have been arranged and fitted with special reference to this fact.

It is also well recognized that the closer the discharge-valve approaches the receiving-valve on the downward stroke of the piston the greater the amount of fluid pumped, and the pump herein presented has been constructed with special reference to utilizing this principle to a maximum degree.

A further object sought to be obtained is to provide a pump which will remain at the bottom of the well during the working thereof; 35 and another object is to provide means for the oil circulation to prevent sand settling around the bottom of the pump and to provide a vent outside of the fluid-chamber for the escape of gas.

The invention further includes the details of construction to be hereinafter set forth, and particularly pointed out in the claims.

The invention is illustrated in the accompanying drawings, in which—

Figure 1 is a side elevation of the lower portion of the pump. Fig. 2 is a longitudinal sectional view of the same. Fig. 3 is a detail of the cage of the inlet-valve. Fig. 4 is a de-

tail of the discharge-valve and contiguous parts.

As the invention relates only to that part of the pump inserted in the well, the accompanying drawings only illustrate that part of the apparatus.

The ordinary deep well is provided with a 55 tubular casing, and the apparatus here shown is designed to be fitted or inserted therein. This part of the pump comprises an upper tubular cast head *a*, a lower head *b*, and a tubular coupling-barrel *c*, providing an oil-chamber, in which the plunger works. The heads are of a diameter to snugly fit the well casing or lining and are each provided with threaded nipples *e e'*, upon which the barrel *c* screws. Each head is further provided with passages 60 *d*, extending longitudinally through the same outside of their axial chambers, which provides means for the circulation of oil to prevent sand settling at the lower end of the head *b* and, in addition, vents for the escape of gas. 70 The head *b* is, in addition, provided with a plurality of radial passes leading through the wall thereof for the passage of the oil as it is sucked in during the upstroke of the plunger, as will be hereinafter described. The axial 75 passage or bore through the head *b*, which opens into the chamber formed by barrel *c*, is controlled by a gravity-valve, which in the present instance is confined by a suitable cage. The valve shown is a metallic ball *f*, 80 which finds a seat on the edge of a ring washer *g*, located in an annular recess in the inner periphery of the nipple *e'*. This washer is retained in place by the valve-cage *e²*, which is threaded into said nipple and which finds 85 a bearing upon a peripheral flange thereon. The valve is drawn off its seat by the suction created by the plunger-head during the upstroke thereof, which is reciprocated in the usual manner.

The upper head *a* is provided with a sleeve *h*, forming a lining therefor, which guides the tubular plunger-rod *i*. This sleeve is made readily removable, so that it may be replaced when worn, and to effect this end it is retained 95 in place by lock-nuts *h'*, threaded on each

end thereof and screwed tightly against the adjacent ends of the head. The plunger-head is valved to provide for the passage of the fluid upward through the tubular rod.

5 The valve is designed to be removed from its seat during the downward stroke of the plunger and to resume its seat as soon as the plunger commences its return stroke. As before stated, the plunger-head works entirely within the barrel *c*. In the structure of the head herein shown, which is the best embodiment of this part of our invention of which we are now aware, the valve *m* is carried by an axial stem *n*, depending axially from a 15 yoke *o*, secured to the lower end of the plunger-rod *i*. As shown, the stem *n* is secured at one end in the valve *m* and extends at its opposite end through an enlarged central portion of a bar *o'*, connecting the ends of the 20 yoke. The yoke is connected, by means of an internally-threaded integral ring *o''*, to the rod *i*, said ring being screwed upon the lower end of said rod. Screwed upon the exterior of this ring *o''* and depending therefrom is a 25 cylinder *r*, in which a tubular member or sleeve *s* is guided, said sleeve being provided with a flanged lower edge *t'*, providing a seat for the valve *m*. The cylinder *r* also confines and guides a spiral spring *t''*, which finds a 30 bearing at one end upon the ring *o''* and presses at its opposite end upon the sleeve *s* to exert a tension to hold the valve-seat upon the valve *m*. The flange *t'*, in addition to providing a seat for the valve, also provides an enlarged pressure-surface to be acted upon by 35 the fluid in barrel *c* to unseat the valve, as will be described hereinafter. The outer edge of the flange *t'* does not fit snugly against the inner periphery of the barrel *c*, but a sufficient clearance is provided to prevent the 40 formation of a vacuum during the upstroke of the plunger.

In assembling the parts of the pump the inlet-valve and coacting parts are fitted to the 45 lower head and the latter screwed into the barrel *c*. The lining-sleeve *h* of the upper head *a* is then inserted in the latter and locked in place by nuts *h'*. The plunger-rod is then passed therethrough, the plunger-head being 50 passed into the barrel *c*. The apparatus is then inserted in the well, the heads *a b*, as before stated, snugly fitting the same. Then the proper length or section of tubing is coupled to the rod *i* to properly connect it with its 55 reciprocating medium.

In operation during the upstroke of the plunger the lower valve *f* will be drawn from its seat, and the oil flowing in through head *b* will enter chamber *c*. During this stroke 60 the valve *m* is held tightly against its seat by the spring *t''* pressing against the sleeve *s*. On the downstroke of the plunger the valve *m* will be forced from its seat, as the resistance offered by the fluid in the chamber *c* to the

downward movement of the plunger-head 65 pressing against the flange *t'* of the sleeve will be sufficient to overcome the force exerted by the spring *t''*, and the sleeve will consequently be pressed upwardly within the cylinder *r*, thus removing the valve-seat from 70 the valve.

It is important that the lower head of the pump be maintained in the bottom of the well, and for this purpose the upper and lower heads are made of heavy castings. The compression of the fluid beneath the plunger-head in the downward movement of the plunger also serves to press the pump to the bottom of the well. 75

All the parts of the apparatus which are 80 subjected to wear are made of steel tubing, and as these parts may be readily removed and replaced when worn the entire pump is practically indestructible.

Having thus described our invention, what 85 we claim as new, and desire to secure by Letters Patent, is—

1. A pump substantially as described, including a tubular plunger-rod and a plunger-head comprising a yoke secured to the end of 90 said rod, a stem depending therefrom, a valve carried by said stem, a cylinder also depending from said rod, and a movable valve-seat guided therein, substantially as described.

2. A pump substantially as described, including a tubular plunger-rod, and a plunger-head, comprising a yoke secured to the end of said rod, a stem depending therefrom, a valve carried by the stem, a cylinder also depending from said rod, a sleeve guided in 100 said cylinder providing a seat for the valve, and a spring for exerting the tension on said sleeve, substantially as described. 95

3. A pump substantially as described, including a tubular plunger-rod and a plunger-head comprising a yoke secured to the end of said rod, a stem depending therefrom, a cylinder also depending from said rod, a valve secured to the end of said stem, a sleeve guided in said cylinder having an outwardly-extending flange at the lower end of the same, 105 providing a seat for the valve, and an enlarged pressure area and a spring for exerting a tension on the sleeve, substantially as described. 110

4. A pump substantially as described, including a tubular plunger-rod, and a plunger-head comprising a yoke secured to the end of said rod, a valve supported therefrom, a cylinder secured to said rod, a sleeve guided 115 in said cylinder, and a flange on said sleeve extending beyond the periphery of the cylinder to provide a seat for the valve, and a stop to limit the upward movement of said sleeve, substantially as described.

5. A pump substantially as described, including a tubular plunger-rod, and a plunger-head comprising a yoke having an inte- 125

gral ring threaded on said rod, a cross-bar forming a part of said yoke, a stem depending axially therefrom, a valve screwed upon said stem, a cylinder screwed upon the exterior of said ring, and depending therefrom, a sleeve guided in the cylinder providing a valve-seat, and a spiral spring interposed between said ring and sleeve, and confined within the cylinder, substantially as described.

In testimony whereof we affix our signatures in presence of two witnesses.
